United States Patent Office.

JOHN EDWARD INSLEY, OF PHILADELPHIA, PENNSYLVANIA, ASSIGNOR TO HIMSELF
AND JAMES FALLOWS, OF SAME PLACE.

Letters Patent No. 91,637, dated June 22, 1869; antedated June 11, 1869.

IMPROVEMENT IN CURRY-COMBS.

The Schedule referred to in these Letters Patent and making part of the same.

To all whom it may concern:

Be it known that I, JOHN EDWARD INSLEY, of the city of Philadelphia, in the State of Pennsylvania, have invented a new and useful Improvement in the Curry-Comb; and I do hereby declare that the following is a full, clear, and exact description of the construction and operation of the same, reference being had to the accompanying drawings, making a part of this specification, in which—

Figure 1 is a central longitudinal section, and Figure 2, a plan view of the said improved implement.

Like letters of reference indicate the same parts when in both figures.

The object of my improvement is to afford a better command of the implement while using it, and, also, to enable the operator to use it with more efficiency and facility for the purpose, and with less annoyance to the horse.

My invention consists in dispensing with the long wooden handle, projecting from one edge of the back of the curry-comb as heretofore, by the application of a loop of leather, or other similar strong, flexible material, to a circular plate of sheet-metal, or its equivalent, secured so that it can be rotated freely in a corresponding opening in the centre of the back of the curry-comb, substantially as hereinafter described.

Referring to the drawings—

A B is the back of the curry-comb;

C, the loop of leather; and

D, the circular plate of sheet-metal.

The drawings represent the implement in full size.

A round hole, about two and a half inches in diameter, is made through the middle of the back A B, and the edge of the plate then raised so as to produce a half bead, a' , around the said hole, and thus afford a circular or annular recess beneath it, for the reception of the edge of the circular plate D, which is made concavo-convex, and of such a diameter as will cause or allow it to fit loosely in contact with the under side of the raised edge a' , when applied from the under side of the back A B, as represented in the drawings.

The loop C consists of a strip, about two and a quarter inches wide, of band-leather, or its equivalent, fastened by rivets $c' c' c'$, or otherwise, through its lapping ends, across the middle of the upper or convex side of the circular plate D, so as to produce a loop which will readily admit the palm of the operator's or holder's hand. (See fig. 2.)

The teeth-plates of the implement are applied in the usual manner, and those directly beneath the circular plate D, when the latter is in place, support and keep it in its proper position in the recess a' , and so

as to permit the back, together with all its teeth-plates, to be easily rotated on the said plate D.

The usual knock-bar b' is riveted fast to the back A B, with the central or middle teeth-plate b'' between. (See fig. 1.)

In the operation of this curry-comb, it will be understood that when the user inserts the palm of his hand into the loop C, he will have a more sure and perfect command of the implement than heretofore, as he will be able to turn it with perfect facility in any direction, and to graduate the pressure with more accuracy, and without any liability of letting it fall, and with less danger of breaking or bruising the skin of the animal about the joints and other bony parts, because, when the palm of the operator's hand is within the loop C, the ends of his fingers and thumb, and the rear portion of the palm of his hand will rest directly upon the back of the comb, and thus enable him to either turn the same with perfect facility in any required direction around the circular plate D, or to prevent it from being turned while using it; and the curry-comb being always in contact with the under side of his hand, he can feel exactly the degree of pressure with which the comb is applied to the animal, and can, therefore, better modify the pressure, and more accurately guide the comb over and around the joints and other protuberances and cavities, for the same reason that sand or emery-paper, when directly under the hand or fingers of the cabinet-maker, or the hand scrub-brush grasped by the hand of the user, affords better facilities for using it properly over rounded projections and in small cavities, than if the same implement were held by a stem-handle, projecting therefrom, as in the old curry-comb.

I am aware that a loop for the hand has been applied to a curry-comb, but the application was made by fixing it rigidly and directly to the back, and therefore not permitting the changes in the direction of the motion of the teeth-bars, as are constantly required to prevent injury to the animal, without inconveniently changing the direction of the motion of the operator's hand.

What I claim as my invention, and desire to secure by Letters Patent, is—

The loop C and plate D, in combination with the back A B of a curry-comb, the said parts being constructed and arranged to operate together, substantially as and for the purpose described.

J. E. INSLEY.
